UNITED STATES PATENT OFFICE.

HENRY W. WINTER, OF METHUEN, MASSACHUSETTS, ASSIGNOR TO UNITED SHOE MACHINERY COMPANY, OF PATERSON, NEW JERSEY, A CORPORATION OF NEW JERSEY.

CLUTCH.

981,345.

Specification of Letters Patent. Patented Jan. 10, 1911.

Original application filed September 28, 1908, Serial No. 455,113. Divided and this application filed May 14, 1909. Serial No. 495,849.

To all whom it may concern:

Be it known that I, HENRY W. WINTER, a citizen of the United States, residing at Methuen, in the county of Essex and State 5 of Massachusetts, have invented certain Improvements in Clutches, of which the following description, in connection with the accompanying drawings, is a specification, like reference characters on the drawings indicating like parts in the several figures.

This invention relates to clutch mechanisms and more particularly to a mechanism which is primarily adapted for use in machines for operating upon shoe soles such, 15 for example, as that shown in my application for United States Letters Patent No. 455,113, filed Sept. 28, 1908, the present application being a division of the above mentioned application.

20 Machines for performing various specific operations upon soles are in use in which the marginal part of a sole is advanced by feeding mechanism against a tool for performing the desired operation. In machines 25 of this class it is desirable that provision be made for varying the speed at which the feeding mechanism is operated. For example, in operating upon a sole along such an abrupt curve as occurs at the toe, an 30 operator can do better work if the feeding mechanism is adapted to advance the sole against the tool at a speed slower than that at which it is customary to feed the sole while operating upon its more nearly 35 straight marginal portions.

An object of the present invention is to provide an improved clutch mechanism the use of which in a machine of the above class will enable the operator to control accurately 40 the speed of operation of the feeding mechanism.

To this end the present invention comprises the improved clutch mechanism hereinafter described and claimed.

45 In the drawings.—Figure 1 is a view in side elevation of a portion of a channeling machine provided with a clutch mechanism embodying the present invention; Fig. 2 is a detail view, partly in section, of the clutch 50 mechanism shown in Fig. 1.

Referring to the drawings, 2 indicates a driving shaft, journaled in a frame 4, which may be arranged to operate the feeding mechanism of the machine by means of suit-

able gears such as shown in my application 55 above mentioned. A driving pulley section 6 is mounted upon a sleeve 8 arranged about the shaft 2 concentrically therewith but secured to the frame 4. A driven section 10 is pinned to the shaft 2 for limited movement longitudinally thereof and a coiled spring 12 seated on a collar 14 is arranged between the sections to move them apart. The collar 14 is provided upon its end adjacent the driving section with a peripheral 60 flange 16 against which one end of the spring 12 presses and said collar is in engagement with one end of the sleeve 8 so that it cannot exert pressure upon the driving section 6. The driven section 10 may be forced into 65 engagement with the driving section 6 by a crank 18 which is pivotally mounted upon a stud 20 secured to an arm 22 fixed upon the shaft 2.

The outer end of the hub of the driven 75 member 10 is beveled as at 24 and is arranged to be engaged by the ends of levers 26 pivoted at 28 upon the arm 22, the arrangement being such that by approaching movement of the inner ends of the levers 26 the 80 driven section 10 is forced into engagement with the driving section 6. To this end a cam 30 carried by the crank 18 is arranged between the levers 26 and for engagement with their inner faces in such manner that a 85 slight swinging movement of the crank serves to press the levers into operative engagement with the beveled end of the hub of the driven section to force said section toward the driving section. Pivotal movement of the crank 18 upon the arm 22 is 90 limited by screws 32 which are engaged by a lug 34 formed upon the crank.

It will be seen that in the clutch mechanism shown the driving section 6 is sustained 95 independently of the shaft 2 and in the inoperative position of the parts is free from frictional engagement with the driven section 10. This is of advantage in that it renders the control of the driving mechanism more 100 sensitive and also because it insures that when the machine is idle the shaft 2 and the crank mounted thereon will not be in rotation.

In the use of the clutch mechanism shown 105 the operator turns the crank in the direction that the driving section 6 is being rotated so that the driven section is forced into en-

2
gagement with the driving section. As the driven section rotates the operator turns the crank and presses the same sufficiently forward to cause the two sections of the clutch 5 to be held in operative engagement. By moving the crank at a slower rate than the speed of the driven section the two sections may be caused to move apart under the influence of the spring 16 so that the operator 10 can conveniently render the clutch mechanism inoperative. It will be seen therefore, in a machine having a clutch mechanism such as that shown, that the operator has a convenient means for regulating the operation of the feeding mechanism so that the 15 advance movement of the sole may be made as slow as desired in operating upon the toe.

It will be understood that the present invention is not limited for use with machines 20 for operating upon soles, as clutch mechanisms embodying the invention may be employed with advantage in other kinds of machines without departing from the scope of the invention.

25 Having described my invention, what I claim as new and desire to secure by Letters Patent of the United States is:

1. In a machine of the class described, the combination with a shaft for transmitting 30 motion to feeding mechanism, of a driving pulley mounted concentrically with the shaft and supported independently of said shaft, a friction member secured to the shaft, a crank arranged for manipulation by the 35 operator supported upon the shaft for a limited amount of movement relatively to the shaft about an axis extending longitudinally of said shaft, and means actuated by said crank for pressing said member and 40 pulley into frictional engagement.

2. In a machine of the class described, the combination with a shaft adapted to transmit motion to feeding mechanism, of a driving pulley mounted concentrically with the 45 shaft, a friction member secured to the shaft, a coiled spring arranged about the shaft for separating said pulley and friction member and supported independently of said pulley

in position to be unaffected by the rotation of said pulley, a crank arranged for manipulation by the operator supported upon the shaft for a limited amount of movement relatively to the shaft about an axis extending longitudinally of the shaft, and means actuated by said crank for pressing said member and the pulley into frictional engagement. 55

3. In a machine of the class described, the combination with a shaft having operative engagement with feeding mechanism, of a 60 driving pulley mounted concentrically with the shaft, a friction member secured to the shaft, an arm fixed to the shaft, cam levers pivoted upon the arm and provided with wedging surfaces arranged to have engagement with different portions of the hub of 65 said friction member, and a crank pivoted upon the arm and provided with a cam member arranged between said levers for simultaneously forcing them into engagement 70 with said hub.

4. In a machine of the class described, the combination with a shaft adapted to transmit motion to feeding mechanism, a driving pulley mounted concentrically with the shaft 75 and supported independently of said shaft, a friction member secured to the shaft, a spring arranged about the shaft for separating said pulley and friction member and arranged independently of said pulley in position to be unaffected by the rotation of the pulley, and a crank arranged for manipulation by the operator supported upon the shaft for a limited amount of movement relatively to the shaft about an axis extending 80 longitudinally of the shaft, and means actuated by said crank for pressing said member and the pulley into frictional engagement. 85

In testimony whereof I have signed my name to this specification in the presence of 90 two subscribing witnesses.

HENRY W. WINTER.
